Inventor:

Hermann Emil Windrath,
By Joseph W. Shaking
Attorney.

UNITED STATES PATENT OFFICE.

HERMANN EMIL WINDRATH, OF AIX-LA-CHAPELLE, GERMANY.

HYGIENIC HEAD-REST.

SPECIFICATION forming part of Letters Patent No. 624,717, dated May 9, 1899.

Application filed October 9, 1897. Serial No. 654,718. (No model.)

To all whom it may concern:

Be it known that I, HERMANN EMIL WINDRATH, of Aix-la-Chapelle, in the District of Aix-la-Chapelle, Prussia, Germany, have invented certain new and useful Improvements in Head-Rests, of which the following is a complete specification, reference being had to the accompanying drawings.

The object of my invention is to produce an improved head-rest for barbers' chairs and the like that is designed to promote cleanliness and afford protection to the occupant of the chair from infectious skin diseases.

Chairs ordinarily employed by hair-dressers and barbers, for example, in their business are provided with rests that are usually adjustable and are designed to support the head and neck of an occupant of the chair. Such head-rests are used for all comers and are not only objectionable to persons of fastidious tastes, but in some instances serve, as is confirmed by medical opinion, as the vehicle of communication of disease from one occupant of the chair to another.

By my invention a head-rest of the kind referred to is provided with a superficial covering which may be changed for each customer, thereby affording a clean and unused support for the head of each new occupant.

In the accompanying drawings, Figure I is a perspective view of a portion of a chair provided with my head-rest, showing an occupant seated in the chair. Fig. II is a front view of the head-rest detached, showing the outer layer or covering partially removed. Fig. III is a sectional view on the line A B of Fig. II. Fig. IV is a side elevation of the subject-matter of Fig. II. Fig. V is a lower edge view of Fig. II, looking upwardly. Fig. VI is a section on the line C D of Fig. II.

Referring to the figures on the drawings, 1 indicates the head-rest support or frame-piece, which is of any suitable shape, dimensions, and contour and made of any suitable material—for example, wood. It is adapted to be attached to a chair by any suitable means—for example, a hinge connection 2—whereby it may be adjusted upon a chair in use.

The inner face of the frame 1 is provided, preferably around its upper edge, with an in-turned flange 3 and on the lower side with suitable fastening mechanism—for instance, screw-clamps or buttons 4. The flange 3 and the fastening mechanism (represented by the

elements 4) are designed to detachably support a suitable protective covering for the frame 1.

I prefer to construct the covering with a base 5 of stiff material—as, for example, cardboard—that fits under the flange 3 and may be secured thereto, as by the clamps 4. The base 5 carries a series of layers 6 of suitable material, preferably sheets of paper or parchment, which afford a cushion upon the head-rest frame 1. The base 5, with its layers 6, constitutes what may be called a "pad" or "cushion" for the head. Each individual layer may be so prepared that no moisture, as of perspiration or the like, can penetrate it, so that only the topmost sheet is affected in use. By this arrangement the top layer of paper may be removed after it has been once used and the next succeeding layer of the series presented for use until each layer of the series has been exhausted, when the base 5 may be removed and a new base, with its layers of paper, inserted in place.

The sheets of paper upon the base 5 may be of any desired shape; but I prefer to provide them with a depending tailpiece, which, falling over the upper portion of the back of the chair to which the head-rest is attached, may serve as a protection for the neck as well as for the head of the occupant of the chair.

As a means of putting a check on the amount of work done by the operators the sheets of each pad may be consecutively numbered. Each sheet as it is stripped off with its number attached indicates that the chair has been occupied and the workman is therefore chargeable for its use.

What I claim is—

1. As a part of a head-rest, a frame provided on one side with a retaining-flange, and on the opposite side with buttons to securely hold a pad in position, substantially as set forth.

2. In a head-rest pad, the combination with a base, of a plurality of superimposed layers, each of the layers being provided with a tail-piece constituting a neck protection, substantially as set forth.

In testimony of all which I have hereunto subscribed my name.

HERMANN EMIL WINDRATH.
